United States Patent Office

Des. 186,562
Patented Nov. 3, 1959

186,562

ROTATABLE BARBECUE

Truman E. Phillips, Santa Barbara, Calif., and Roy D.
Laws, Portland, Oreg.

Application September 8, 1958, Serial No. 52,534

Term of patent 7 years

(Cl. D81—7)

We claim:

The ornamental design for a rotatable barbecue, substantially as shown.
